(57) **CLAIM**

The ornamental design for a clothes treating apparatus, as shown and described.

DESCRIPTION

FIG. 1 is a perspective view of a clothes treating apparatus showing our new design.

FIG. 2 is a front elevational view of a clothes treating apparatus showing our new design.

FIG. 3 is a left side elevational view of a clothes treating apparatus showing our new design, the right side elevational view being a mirror image; and,

FIG. 4 is a top plan view of a clothes treating apparatus showing our new design.

The broken lines shown in FIGS. 1-4 are for environment and form no part of the claimed design.

The bottom and rear of the clothes treating apparatus form no part of the claimed design.
